UNITED STATES PATENT OFFICE.

OTTO S. BEYER, OF BROOKLYN, NEW YORK, ASSIGNOR, BY MESNE ASSIGNMENTS, TO
E. W. BLISS COMPANY, OF BROOKLYN, NEW YORK, A CORPORATION OF DELAWARE.

THIN-WALLED METAL RADIATOR.

Application filed February 4, 1926. Serial No. 86,075.

This invention relates to thin-walled metal radiators, and aims to provide certain improvements therein. More specifically, it has to do with improvements in radiators comprising thin-walled tubes provided with means for reinforcing the same against excessive deformation due to the high pressure of the fluids used therein and the wide variation of temperature changes to which they are subjected, and for increasing the effective area of radiating surface, as described in my copending application Serial No. 12,055, filed February 27, 1925.

According to the present invention, instead of forming the radiator sections from short lengths of tubing, as described in my aforesaid application, I form a plurality of sections from a single length of prepared tubing by appropriately bending it preferably into a sinuous form. By so doing, the number of joints and the possible sources of leakage are reduced to a minimum. Suitable means are also provided for preventing detrimental deformations of the sections when subjected to high pressures and wide temperature variations of the fluids used therein, which means are also so designed as to provide a maximum of efficient interchange of temperatures between the fluid medium used in the radiator and the air to be treated thereby.

The present invention also provides a radiator having a weight, volume and cost much less, and an efficiency based on said factors much greater than the usual types of radiators.

Several embodiments of the invention, and the article in several stages of manufacture illustrative of the method, are shown in the accompanying drawings, in which

Figs. 1 and 2 are respectively an end and a plan view of one embodiment.

Figs. 3 and 4 are sectional views on the lines III—III and IV—IV of Fig. 1.

Fig. 5 is a view in elevation with parts broken away of another embodiment of the invention.

Figs. 6 and 7 are sections taken on the lines VI—VI and VII—VII of Fig. 5.

Fig. 8 is a view similar to Fig. 5 of still another embodiment.

Figs. 9 and 10 are sections taken on the lines IX—IX and X—X of Fig. 8.

Figs. 11, 12, 13, 14 and 15 are views showing the radiator tubes in several stages of the method of manufacture.

Referring first to Figs. 1 to 4 of the drawings, let 10 indicate a radiator which may consist of one or more units grouped or coupled together, each unit comprising a plurality of substantially straight portions or sections 11 and a plurality of U-shaped portions or bends 12 connecting adjacent sections in such manner that each intermediate section 11 connects with two adjacent sections. The end sections of each unit may have connections at one end, as indicated at 13, or at both ends, as 13 and 14, according as the fluid medium to be used therein is a gas, vapor or liquid, or as may be necessary or desired.

The sections and bends of each unit are preferably formed from a long thin-walled tube 15 which is flattened throughout its length excepting at its ends, as will be more fully explained, and said tube, which has a length of a plurality of sections and bends, is preferably sinuously bent, as shown in Fig. 1. The tube 15 being flat or substantially flat, it will be appreciated that the ratio of radiating surface to volume will be large and that the bends 12 may be made relatively sharp.

The radiating effect may be further increased by providing separately formed radiating means 30, 31 in contact with the outer surface of the sections 11. These means 30, 31 are conveniently sheets or strips of metal, preferably stamped to substantially surround the radiator sections, and preferably provided with projections 33 (here shown as drawn projections, preferably open at the sides as indicated at 35, Fig. 4), adapted to provide a copious temperature interchange between the mediums on the inner and outer sides of the radiator 10. These projections 33 may be arranged to nest one within a space between two projections on

the opposite strip 30, 31, and the projections further more are conveniently arranged to bear on the opposite strip 30, 31, and when so arranged, act to support the sections 11 against bulging, which arrangement is desirable where internal pressures are relatively high. The radiating strips 30, 31, themselves may by their own stiffness and by being fastened together, reinforce the sections 11 against bulging. Preferably the strips 30, 31 are so formed that when used in pairs around a radiator section they will substantially entirely surround the same.

Where a continuous circulation through the radiator is necessary, as of hot water, brine, etc., or desired, the ends 13, 14 of the radiator tubes 15 are left open and connections made to the supply and leading off pipes 42, 43. Where there is no condensation, the location of the inlet and outlet is immaterial.

The tube 15 is preferably reduced in diameter at its end or ends 13, 14 to an extent where the area of the reduced end is equal to or approximately equal to the area of the cross section of the flattened parts of the sections 11, and the reduction of diameter of the end of the tube is preferably effected in such manner as to thicken the walls of the tube at its reduced end or ends. The area enclosed by the end of the tube 13 shown in Fig. 3 is preferably approximately equal to the enclosed cross sectional area of the flattened part of the tube 12 shown in Fig. 4. Moreover, by comparing the thickness of the walls of the tube, at the end 14, and at the flattened part, the greater thickness of the wall at the end 14 will be seen. The equal cross sectional area of the end or ends, and of the sections 11 provides for a rational flow of the fluid medium in or through the radiator 10. The thickened ends also provide a greater body of metal, and consequently a more rigid structure at the joints between the radiator and the supply line 42, or carry off 43.

Where a copious interchange of temperatures of fluid mediums is desired, as in industrial uses (air conditioning apparatus, cooling apparatus, heating apparatus, refrigerating apparatus, &c.) a number of radiator units may be grouped together, as shown in Fig. 2, and connected to supply and carry-off pipes 42, 43 in the form of manifolds, as shown in said Fig. 2. Plates 50, 51 or equivalent means may be used for confining the group of radiator units together and these plates connected by the rods 53 or the like.

In thin-walled radiators comprising sections, it will be appreciated that unequal expansion of the sections, caused when the fluid medium admitted to the inside of the radiator, is at a decidedly different temperature from that of the medium on the outside

of the radiator, will produce a strain, not only in the particular section affected, but throughout the radiator. And where these sections are confined at each end the sections and the joints are intermittently strained, and in course of time develop cracks or looseness of the joints, thereby rendering the radiator useless, but worse still, frequently result in costly destruction of other things due to the leaking of the medium circulating inside of the radiator sections. In the present construction the sections are free to expand and contract unequally. Such strains as are produced, are transmitted through a plurality of the sections, and the extent and consequences thereof is therefore minimized.

In Figs. 5-7, I have shown a radiator 60, the flattened tubes 15 of which are bent into the form of a flattened helix, comprising sections 61, connected by bends 65, to provide a unit structure having spaced substantially flat parallel walls. Surrounding these walls and in contact therewith for the purpose of increasing the effective area of radiating surface, are sheet metal plates 66, 67 formed with projections or ribs 68, which are preferably struck up from the body of the plates. These projections 68 are formed in rows to coincide with the sections 61, and are preferably inclined to the longitudinal axes of said sections. Also, the adjacent rows of projections are inclined in opposite directions, so as to provide zig-zag air passages over the radiator surfaces. It is also desirable that the plates 66 with their projections shall snugly fit between the inner walls of the helix and be so arranged with respect to each other that the projections on the respective plates will cross each other, thereby bracing and reinforcing the sections against unequal strains. The plates 67 which contact the exterior walls of each helix and encompass the same may be secured together at their edges adjacent the bends 65 in any desired manner, as by bolts 69 and nuts 70.

It will be apparent that any number of unit structures 60 may be grouped together to provide a radiator having a predetermined temperature interchange capacity. In Figs. 5-7, a group consisting of two such units is illustrated, each unit having an open end 71 adapted for connection with a source of fluid and an outlet end 72 through which the fluid may be discharged. Obviously these ends 71, 72 may be connected to manifolds, as shown in Fig. 2.

In Figs. 8-10, I have shown a radiator especially adapted for use in homes, offices, etc., where the amount of space available for radiators is limited. With this type of radiator, because of its large effective area of radiating surface, it is possible to obtain a far greater heating effect per unit volume of radiator than with the conventional types of cast radiators. Hence, for equal heating

effects, a much smaller radiator of the present type will do the work of a larger cast radiator. The temperature interchange between the present radiator and air may be 5 also augmented through the use of a blower in combination with the radiator.

A preferred embodiment of this type of radiator consists of a unit structure 60, as shown in Figs. 5-7, confined within a suitable housing 73, which may consist of a base 74, a casing 75 and a top 76. For insuring the maximum efficiency and esthetic appearance, the casing may be ornamented through an artistic arrangement of openings 77.

In the various embodiments illustrated it will be apparent that the radiator may be arranged for use with a gas or vapor, which liquefies at the temperature and pressure of 20 use, in which event only one open end, such as 13 in Figs. 1 and 2 and 71 in Figs. 5-10 connected to a source of fluid supply will be necessary. It is preferable that where but one opening is used, that it be located at the 25 low point of the radiator.

The method of manufacturing the radiator is substantially as follows:

A tube 15, (Fig. 11) preferably of the length of a plurality of the sections 11 or 61 30 of the radiator to be formed therefrom, and having relatively thin walls, is taken, and the end or ends 13, 14 or 71, 72 are reduced in diameter, and the walls at the end preferably thickened, as heretofore explained. 35 The reduction of the end or ends is preferably accomplished by the hammering action of a machine having a shape of hammer and anvil, which results in the formation of a conical portion at the end or ends of the 40 tube. See Fig. 12.

The ends of the tube are then drawn out to provide cylindrical portions 16 after which the tube 15 intermediate its cylindrical ends is then flattened, as indicated in Figs. 14 and 45 15, the operations of flattening and of reducing the end or ends being so related that an approximate equality of area of the cylindrical ends, and of the flattened part, is attained.

50 The flattened tube is thereafter sinuously bent into a plurality of sections, as illustrated in either Figs. 1 and 2 or Figs. 5-10, the bending being preferably done so that there is a slight convergence toward the bend, between every two adjacent sections of each unit, so that the radiator may be readily drained.

Thereafter the end or ends to be joined to the supply line are fashioned suitably for 60 connection to the supply line, as by being threaded, or as by having a threaded bushing 80 attached thereto by expansion of the tube into the bushing or by brazing or the like.

The article of this invention may receive 65 other embodiments than those herein specifically illustrated and described, and the method of manufacture may be carried out with variations in the mode of procedure specifically described. 70

What I claim is:

1. A radiator comprising a thin-walled flattened tube sinuously bent in the form of a plurality of sections, and means in contact with said sections for increasing the effective area of radiating surface, said means comprising sheet metal strips disposed to substantially entirely envelop the sections, said strips having projections thereon, and the sheet metal strips on adjacent sections 80 having parts thereof in contact, thereby bracing and maintaining the sections in spaced relation to each other.

2. A radiator comprising a flattened tube bent in the form of a plurality of sections, 85 and means for increasing the effective area of radiating surface, said means comprising sheet metal elements in contact with a plurality of sections, said elements having projections thereon, the projections on one element engaging and crossing projections on the element of an adjacent section. 90

3. A radiator comprising a flattened tube bent in the form of a plurality of sections, 95 and means for increasing the effective area of radiating surface, said means comprising sheet metal elements in contact with a plurality of sections, said elements having projections thereon arranged in inclined relation to the axes of the sections and the projections on one element engaging and crossing the projections on the element of an adjacent section. 100

4. A thin-walled metal radiator comprising a flattened tube bent in the form of a 105 flattened helix providing a structure having spaced substantially flat parallel faces, and means in contact with said parallel faces for increasing the effective area of radiating surface. 110

5. A thin-walled metal radiator comprising a flattened tube bent in the form of a flattened helix providing a structure having substantially flat parallel walls, and sheet metal elements in contact with the exterior 115 walls of the structure and secured together at the bends of the helix, said elements having means for increasing the effective area of radiating surface.

6. A thin-walled metal radiator comprising a flattened tube bent in the form of a flattened helix providing a structure having spaced substantially flat parallel faces, and means in contact with said parallel faces for increasing the effective area of radiating surface, said means having projections thereon in inclined relation to the axes of the convolutions of the helix. 120 125

7. A thin-walled metal radiator comprising a flattened tube bent in the form of a flattened helix providing a structure having spaced substantially flat parallel faces, and
5 means in contact with said parallel faces for increasing the effective area of radiating surface, said means having projections there-
on in inclined relation to the axes of the convolutions of the helix and so positioned in relation thereto as to provide zig-zag air passages over the radiator surfaces. 10

In witness whereof, I have hereunto signed my name.

OTTO S. BEYER.
